(57) **CLAIM**

The ornamental design for a fixing rod as shown and described.

DESCRIPTION

FIG. 1 is a top, front and left side perspective view of a fixing rod showing my new design;
FIG. 2 is a bottom, rear and right side perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of portion 9 thereof; and,
FIG. 10 is an enlarged view of portion 10 thereof.
The broken lines in FIGS. 7 illustrate portions of the fixing rod which form no part of the claimed design.
